SURFACE ORNAMENTATION OF WALLS.

No. 18,479.

Patented July 24, 1888.

UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,479, dated July 24, 1888.

Application filed March 17, 1888. Serial No. 267,573. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

The accompanying photograph represents my design.

Similar letters of reference indicate like parts.

My design consists in groups A of quadrangular elevations, as B, each group showing the same number of said elevations. Each

elevation is pyramidal in form, and has four 15 outwardly-curved or convex faces, as C. Between the elevations forming a group are narrow channels, as D and E. Between the groups A of elevations are wide channels, as F G.

I claim—

The design for surface ornamentation of walls, &c., substantially as herein shown and described.

FREDERICK KOSKUL.
